UNITED STATES PATENT OFFICE

WALTER O. SCHMIDT, OF HACKENSACK, AND CHARLES HABERMAN, OF NORTH BERGEN, NEW JERSEY, ASSIGNEES TO OSCAR SCHMIDT, INC., OF JERSEY CITY, NEW JERSEY, A CORPORATION OF NEW JERSEY

STRINGED MUSICAL INSTRUMENT

Application filed February 20, 1929. Serial No. 341,362.

The invention relates to stringed musical instruments and has more particular reference to the type known as "Hawaiian guitars", which are usually played with the use of picks on the fingers of the right hand, for the melody, and with a so-called "steel" held in the left hand, for the accompaniment.

It has been found in practice, more particularly in the case of beginners, that the arm manipulating the steel soon becomes tired or cramped, with the result that the pleasure of playing is interfered with, and, in the case of beginners, progress is substantially delayed. Because of this, it has been the object of the present invention to provide the instrument or guitar with a means for supporting the steel in a manner permitting of its manipulation in the playing of the guitar in substantially the same free way as when supported by the player's hand, but without strain or effort on the part of the player in the holding or supporting of the same. This object is accomplished, in a preferred form of the invention, by mounting a supporting rod on the instrument in a position above and lengthwise of the strings, and preferably in a manner permitting of its movement transversely of the strings, and on this rod slidably mounting the steel through the medium of a universal joint connection whereby the steel may be freely manipulated for playing engagement with the strings.

Referring to the accompanying drawings,

Fig. 1 is a plan view of a guitar equipped with a playing attachment embodying the invention.

Fig. 2 is an end view of the same.

Fig. 3 is a cross section through line 3—3 of Fig. 1.

Fig. 4 is a similar view showing the steel in a different playing position.

Fig. 5 is a plan view of the guitar illustrating a modified form of the invention.

Fig. 6 is an end view of the same.

Fig. 7 is a cross section through line 7—7 of Fig. 5.

Fig. 8 is a plan view of the guitar equipped with the invention in a modified form and

showing in full lines the playing attachment folded back to a lowered inoperative position.

Fig. 9 is an end view of the same showing the playing attachment in raised operative position in full lines and in lowered inoperative position, corresponding to the full line position of Fig. 8, in dotted lines.

Fig. 10 is an enlarged cross section on line 10—10 of Fig. 8, showing the playing attachment in raised operative position in full lines.

Fig. 11 is a similar view showing the attachment in its lowered inoperative position in full lines.

To explain in detail, the instrument shown is a so-called "Hawaiian guitar" of usual construction, the same comprising the body portion 2 equipped with strings 3 mounted thereon in usual manner.

In accordance with the invention, a supporting rod 4 is mounted on the body 2 in a position above the strings where they overlie the frets 5; this rod, as shown in Figs. 1 to 4 inclusive, being pivotally mounted for movement in a direction transversely of the strings for a purpose to be presently referred to. As a means for pivotally mounting the rod, the latter is formed at its opposite ends with upturned extensions 6, 6 having short terminals arranged parallel with the rod loosely fitting in the bored upper ends 7, 7 of two bracket arms 8, 8 which latter are fitted at their lower ends in socket pieces 9, 9 in the body 2. These bracket arms 8, 8, which are here shown as being connected with the body 2 at one side of the centrally arranged strings 3, are formed with off-sets in their vertical length in order to position their rod supporting ends or terminals 7, 7 in central position above the strings as shown.

The steel hereinbefore referred to, indicated at 10, has a sliding connection with the rod 4 through the medium of a universal joint connection whereby it may be readily manipulated for playing engagement with the strings. Any suitable connection of the steel with the supporting rod may be employed for this purpose. As here shown, a sleeve 11 is loosely mounted on the rod for longitudinal sliding and turning movements

thereon. This sleeve carries a fixedly connected block 12 to which the steel is attached, by means to be presently described, for sliding and pivotal movements relatively thereto.

5 The steel 10 as here shown is cut away at its center to provide an opening 13 through which the supporting rod 4 extends, whereby the lower edge 10', constituting the steel proper, is in position beneath the rod for engagement with the wires, while the upper portion, constituting the handle, is in position above the rod for convenient grasping by the player.

10 A threaded pin 14, attached to the steel in a position extending vertically across its opening 13, passes loosely through an opening in the block 12 to effect a pivotal connection of the steel with said block. A coiled spring 15 surrounding said pin 14 and expanding 15 between the block 12 and the top wall of the opening 13 in the steel, acts to normally hold the latter in a raised position spaced from the strings.

15 With the steel mounted on the rod 4 in the way shown and described, the player may grasp the upper part of the steel and readily shift the same for usual playing engagement with any one or more of the strings, that is, the steel may be shifted lengthwise of the string by a sliding movement on the rod, as indicated by the full and dotted line positions of the same in Fig. 1; or it may be rocked or tilted on the rod to bring it to an angular position for so-called "tipping" of the strings, 20 as shown in Fig. 2; or it may be moved transversely of the strings by a swinging movement of the rod to permit of its tipping different strings, as shown in Fig. 4; or it may be moved bodily downward against the pressure of the spring 15 for simultaneously engaging all of the strings, as in "barring", as shown in Fig. 3; or it may be swung horizontally about its vertical pivot 14, as indicated by the dotted line positions in Fig. 1, for 25 barring the strings across a plurality of frets, this horizontal turning of the steel also facilitating the manipulation of the same in that it readily adapts itself to the various angular positions assumed by the hand in shifting the steel to its different playing or string engaging positions.

30 Referring now to Figs. 5, 6 and 7, these show a modification of that feature of the invention comprising the support of the rod 4. This rod, as before shown and described, is pivotally supported for movement transversely of the strings. In the modified form, it is supported for movement in a straight line horizontal plane by means of two blocks 20, 35 mounted on the body 2 in a position above the strings by fixed bracket arms 21, 21, said blocks being provided with horizontally ranging elongated slots 22 through which the rod 4 loosely extends at its opposite ends as shown.

40 With the rod thus supported it obviously is

free to be moved back and forth transversely of the strings as may be required in the described manipulation of the steel. As a means for rendering such movement of the rod noiseless, the walls of the slots 22 are lined with felt or like material for engagement by the rod, as indicated at 23.

45 With the rod 4 and its supporting arms 8 mounted in the normal operative position shown in Figs. 1 to 4 inclusive, they add substantially to the height or bulk of the instrument and are accordingly objectionable because of the increased space required, both in their regular holding cases and also in the boxes or other containers employed in shipping the same. For such reason, it has been found desirable to mount the attachment on the body 2 in such manner that it may be readily shifted or folded to an inoperative position where it will lie substantially within 50 the maximum dimensions of the instrument itself. To accomplish this, the bracket arms for carrying the rod 4, as shown in Figs. 8 to 11 inclusive, are provided with pivotal joints, 30, just above the body 2 of the instrument, permitting of the upper sections 8' of the arms, together with the supported parts including the rod 4 and connected steel 10, to be swung or folded back from their normal operative position, as shown by dotted lines in Figs. 8 and 11 and full lines in Figs. 9 and 10, to a lowered inoperative position, as shown by full lines in Figs. 8 and 11 and by dotted lines in Figs. 9 and 10. When the attachment is in this lowered position it lies substantially within the vertical dimensions of the instrument and does not require any substantial increase of packing space over that required for the instrument itself, as will be clear by reference to the drawings.

55 When the attachment is swung up to its operative position, it is held in such position by sleeves 31 slidably mounted on the bracket arms and overlapping both sections 8' and 8" of said arms at their joints 30, such engagement of the arm sections by the sleeves serving to hold the upper one 8' in rigid relation to the lower one 8". When it is desired to fold back the attachment, this may be accomplished by simply raising the sleeves above the joint 30 as shown, whereupon the upper arm sections and supported parts may be swung or folded back to their lowered inoperative positions. A pin or projection 32 on each of the lower arm sections 8" serves as a means to limit the downward movement of the sleeve 31 and retain it in its operative position for holding or locking the upper section in fixed relation to the lower one.

60 What we do claim is:

1. In combination with a stringed musical instrument, a playing attachment comprising a string engaging member, supporting means mounted on the instrument, and means connecting said member with the supporting

- means whereby it is capable of longitudinal, transverse and tilting movements relatively to the strings.
2. In combination with a stringed musical instrument, a playing attachment comprising a string engaging member, supporting means mounted on the instrument, and means comprising a universal joint connecting said member with the supporting means whereby it is capable of tilting movements in both vertical and horizontal planes relatively to the strings. 70
3. In combination with a stringed musical instrument, a playing attachment comprising a string engaging member, supporting means mounted on the instrument, means connecting said member with the supporting means whereby it is capable of tilting movements in both vertical and horizontal planes relatively to the strings, and means yieldingly holding said member in a normal position spaced from the strings. 75
4. In combination with a stringed musical instrument, a playing attachment comprising a supporting bar mounted on the instrument in a position lengthwise of the strings, and a string engaging member mounted on said bar for sliding and tilting movements relatively to the strings. 80
5. In combination with a stringed musical instrument, a playing attachment comprising a supporting bar arranged lengthwise of the strings and mounted for movement in a direction transversely of the latter, and a string engaging member slidably mounted on said bar. 85
6. In combination with a stringed musical instrument, a playing attachment comprising a supporting bar arranged lengthwise of the strings and pivotally mounted for movement in a direction transversely of the latter, and a string engaging member slidably mounted on said bar. 90
7. In combination with a stringed musical instrument, a playing attachment comprising a supporting bar arranged lengthwise of the strings and mounted for movement in a direction transversely of the latter, and a string engaging member mounted on said bar for longitudinal sliding and transverse tilting movements. 95
8. In combination with a stringed musical instrument, a playing attachment comprising a supporting bar arranged lengthwise of the strings and mounted for movement in a direction transversely of the latter, and a string engaging member mounted on said bar for longitudinal sliding and transverse tilting movements and also being yieldingly held on the bar for bodily movement toward and from the strings. 100
9. In combination with a stringed musical instrument, a playing attachment comprising a string engaging member in the form of a straight edged bar of a length sufficient to 105
- engage the full set of strings in a direction transversely thereof, and means supporting said member for universal movement relatively to the strings. 110
10. In combination with a stringed musical instrument, a playing attachment comprising a supporting bar arranged lengthwise of the strings and mounted for movement in a direction transversely of the latter, a collar mounted on said bar for sliding and rocking movements, and a string engaging member carried by said collar for movement relatively to the strings. 115
11. In combination with a stringed musical instrument, a playing attachment comprising a supporting bar arranged lengthwise of the strings and mounted for movement in a direction transversely of the latter, a collar mounted on said bar for sliding and rocking movements, and a string engaging member pivoted on said collar with its axis arranged transversely of the bar. 120
12. In combination with a stringed musical instrument, a playing attachment comprising a supporting bar arranged lengthwise of the strings and mounted for movement in a direction transversely of the latter, a collar mounted on said bar for sliding and rocking movements, a string engaging member pivoted on said collar with its axis arranged transversely of the bar, and a spring holding said member in a normal position spaced from the strings. 125
13. In combination with a stringed musical instrument, a playing attachment comprising a string engaging member, and means supporting said member for movement relatively to the strings, said means comprising a pair of pivotally jointed bracket arms, and means for locking and releasing the joints of said arms, for the purpose specified. 130
14. In combination with a stringed musical instrument, a playing attachment comprising a string engaging member, and means supporting said member for movement relatively to the strings, said means comprising a pair of pivotally jointed bracket arms, and sleeves slidably mounted on said arms for locking and releasing the pivotal joints of the same, for the purpose specified. 135
- In testimony whereof we affix our signatures.
